[57] **CLAIM**

The ornamental design for a toy sand wheel, as shown and described.

DESCRIPTION

FIG. 1 is a front elevational view of a toy sand wheel showing my new design, the rear being a mirror image and the pail shown in broken lines for illustrative purposes only;

FIG. 2 is a left side elevational view thereof;

FIG. 3 is a right side elevational view thereof;

FIG. 4 is a top plan view thereof; and,

FIG. 5 is a bottom plan view thereof.
